Primary Examiner — Cathron Brooks*Assistant Examiner* — Melanie Pellegrini(74) *Attorney, Agent, or Firm* — Jennifer Meredith, Esq.; Meredith & Keyhani, PLLC(57) **CLAIM**

I claim the ornamental design for the gemstone setting, as shown and described.

DESCRIPTION

FIG. 1 is a top and front perspective view of gemstone setting showing my new design;

FIG. 2 is a rear elevational view thereof;

FIG. 3 is a side elevational view thereof;

FIG. 4 is a top plan view thereof;

FIG. 5 is a top and front perspective view thereof shown in an alternate environment; and,

FIG. 6 is a right side perspective view shown in an alternate environment.

The broken lines shown in the drawings represent environmental matter and form no part of the claimed design.
